UNITED STATES PATENT OFFICE

2,390,179

BUILDING CONSTRUCTION

Charles H. Sacks, Brooklyn, N. Y.

Application May 17, 1944, Serial No. 536,015

11 Claims. (Cl. 20—1.1)

My invention relates generally to building constructions, and specifically to building constructions of the multiple-dwelling type. More particularly, my invention relates to multiple-dwelling buildings wherein the rooms of the individual apartment units are disposed on two or perhaps more levels or stories. My invention also relates to buildings containing both single level units and units occupying two or more levels or stories.

This application is a continuation-in-part of my application Serial No. 472,786, filed January 18, 1943.

In the following description of illustrative embodiments of my invention, I will use the term "duplex" to indicate a unit of two or more stories or levels, one above the other.

In conventional multiple-dwelling building constructions, the rooms of any one apartment unit are all disposed on a single level or story. While some multiple-dwelling buildings may, and usually do, have apartment units with a different number of rooms or room arrangements, these different units are arranged with the bedroom, living room, kitchen of one apartment, all on one level, directly over or directly under the bedroom, living room and kitchen, respectively, of the apartments on the story above and below. Building constructions containing duplex units uniformly have these arranged directly above one another, with the bedrooms, living rooms, etc., of one duplex arranged above each other, but on alternate stories or levels. As an example of this latter type of building construction, see the Tullgren Patent No. 1,896,734, granted February 7, 1933.

Duplex apartments, as a rule, afford more privacy and provide more freedom from noises emanating from adjoining apartments than is secured in ordinary multiple-dwelling building constructions. However, duplex constructions proposed heretofore have uniformly failed to realize on the potentialities inherent in duplex construction as opposed to single-story arrangements, and fail to thoroughly isolate each duplex unit from the others as completely as possible. In Tullgren, for instance, the living room level of one series of units is directly below or directly above the sleeping rooms level of the series of units above and below, and the living room levels alternate with sleeping room levels. Unless completely and expensively sound insulated, such proximity permits the noises and, particularly the impact noises, from one unit to annoyingly penetrate through to the adjacent units.

The main object of my invention, therefore, is the provision of a duplex type of multiple-dwelling building construction within which the floor or level arrangements are reversed in one series 5 of duplex apartments from the floor or level arrangements of the series of duplex apartment units immediately above or immediately below.

A further object of my invention is the provision of a building construction of the duplex type 10 in which the floor arrangements of any one series of units are disposed in reverse level relationship to the floor arrangements of the series of units directly above or below.

A further object of my invention is the provision 15 of a building construction of the duplex type in which the living rooms are on one story or level of the unit and the bedrooms are on another story or level of the unit, and the arrangements of living room and bedroom levels are reversed in each 20 vertically successive apartment unit in the building.

Still another object of my invention is the provision of a building construction having duplex 25 units in which the sleeping quarters of one series of units are directly above the sleeping quarters of the units below, and the living quarters of said first series of units are directly below the living quarters of the units above.

Still another object of my invention is the provision 30 of a building having single-level or story units and duplex units, and the level arrangements are reversed in successive duplex units.

Other and further objects of my invention will 35 be obvious and still others pointed out in the following description of an illustrative embodiment. In the drawings annexed hereto, forming a part hereof, in which similar elements will be similarly numbered:

Figure 1 is a roof plan view of a portion of one 40 form of building constructed according to and embodying my invention;

Fig. 2 is a vertical section on the line 2—2 of Figs. 4 and 5;

Fig. 3 is a vertical section on the line 3—3 of 45 Figs. 4 and 5;

Fig. 4 is a floor plan section of the first, fourth and fifth story levels;

Fig. 5 is a floor plan section of the second, third and sixth story levels;

Fig. 6 is a vertical section on the lines 6—6 of 50 Figs. 7 and 8, of a modified form of building also constructed according to and embodying my invention;

Fig. 7 is a floor plan view of the first and fourth 55 story levels of the building shown in Fig. 6;

Fig. 8 is a floor plan view of the second and third story levels of the building shown in Fig. 6;

Fig. 9 is a vertical section through a further modified form of building also constructed according to and embodying my invention; and

Fig. 10 is a view similar to Fig. 3 of this further modification.

In the modification of Figs. 1 to 5 inclusive, I have embodied my invention in a building of six stories or levels, numbered 1, 2, 3, 4, 5 and 6 from the bottom upwards, having three stories of two-storied or "duplex" units. My invention is equally and obviously applicable to a four-, eight-, ten- or more-storied building, to buildings in which the units occupy three stories each, and to buildings which contain single-story units as well as duplex units.

In the form of my invention illustrated in Figures 1 to 5, the building is indicated by reference numeral 10. In a six-level or story building as illustrated, three series of duplex apartments or units are shown, each series occupying two levels, but it is obvious that more duplex units may be provided in a ten-, twelve-, or more-storied building, equally in accordance with my invention. The portion illustrated is generally U-shaped, having a base 12 and wings 14, 14 at right angles thereto. I provide three apartment units in each wing 14 and four in base 12, although, as desired, more or less may be formed in the wings and base, depending on the number and size of the rooms; and, of course, within the scope of my invention the shape of the building may be changed, other wings added, etc., as desired, or as convenient for any particular site.

Referring to Fig. 4, which is a floor plan on the first, fourth and fifth levels of the six-story building shown, access from the outside building 10 may be provided through doors 18, 18 at the rear of the court 16, between the wings and base. Doors 18, 18 open into public hallway 20, which extends around the building. All the apartment units may open onto hallway 20 through doors 22, 22. The apartments on this level are indicated by the letters A, B, C, and so on. The elevator shaft extending from the basement to the fifth floor, is indicated by reference numeral 24. The stairs, from the basement to level 6, are indicated by reference numeral 26.

It will be understood, of course, that my invention may equally well be incorporated in a duplex apartment building wherein the entire length and breadth thereof is occupied by a single apartment, so that, as illustrated in Figs. 6, 7 and 8, building 110 of only four stories or levels, 101, 102, 103 and 104, will make up only two complete duplex units for the entire building. In this form of my invention, there is no need for a hallway as 20.

Referring back to the modification of Figs. 1 to 5, inclusive, the first series of units are made up of rooms on stories 1 and 2. On the first floor level 1, as shown in Fig. 4, unit A provides the living quarters comprising a living room 30, a dining alcove 32 and a kitchen 33. A small wash room or lavatory 35 is also provided on this level. The foyer 34, off the entrance 22, has a flight of steps 36 leading upwards and in communication with the rooms on the second story level (see Fig. 5). On this second story level are the sleeping rooms of unit A comprising a large bedroom 38, a second and smaller bedroom 40, and a toilet or bathroom 42. I have designated the living rooms of all the other units by numeral 30, the dining alcoves by reference numeral 32, the kitchens by

reference numeral 33, the foyers by reference numeral 34, the small lavatories by reference numeral 35, the stairs by reference numeral 36, the bedrooms by reference numerals 38, 40 and the bathrooms by reference numeral 42. It will, of course, be understood that these floor arrangements may be varied within wide limits.

Thus, the duplex apartment units occupying stories 1 and 2 have the living quarters on story 10 or level 1, and the sleeping quarters on story or level 2. There is no normal communication between the several units on story 2, and the stairs 26, which open onto levels 1, 4 and 5, are closed off on levels 2, 3, and 6, as indicated at 50. Secondary means may be provided, such as fire escapes (not shown) or fire tower emergency stairs 51 which extend the full height of the building and open onto balconies 52, 52.

The succeeding series of duplex apartments 20 occupy stories 3 and 4. In this series, the sleeping quarters comprising rooms 38, 40 and 42 are on story or level 3, immediately over the sleeping quarters of the series of duplex apartments on levels 1 and 2. The living quarters comprising rooms 30, 32, 34 and 35 of the second series of units are on level 4, and are thus removed from the sleeping rooms of the unit below on floor 2 by level or floor 3.

According to my invention, therefore, the bedrooms or sleeping quarters of the first series of apartments are on level 2, above the living room floor. The living rooms of the second series of apartments are on level 4, spaced by at least one story from the bedrooms of the first and third 30 series of apartments. The living rooms of the third series of units are on level 5, over the living rooms on level 4, so that this living room level 5 is spaced away from the sleeping rooms of the units on levels 3 and 4 by at least one level or story. However high the buildings of my invention may be constructed, the living rooms of any one series of apartment units are always at least one story removed from the sleeping rooms of the units above and below.

45 As result of my invention, therefore, levels (as 2, 3 and 6) having thereon the sleeping quarters are effectively insulated from noises emanating from the living rooms of the apartment units above and below. This is due to the reversal of 50 the room arrangement in successive apartment units; and to the interposition of at least one story or level between the living rooms of one unit and the sleeping rooms of the units above and below.

55 As will be seen in Figs. 1, 2, and 3, I may provide a roof garden 60 atop each of the topmost apartment units, access thereto being provided via stairs 62 from each unit of the topmost series. Stairs 26 lead to the roof level R, and a passageway 64 is provided common to all of the gardens 60. Shelters as 66 are provided over stairs 62 to protect them against the elements. Shield 68 covers the stairs 26 which lead up onto the roof.

As pointed out above, the elevator shaft 24 65 need not extend all the way up to and above the roof level. I have thus been able to eliminate the expense and space of extending the elevator shaft as high as is ordinarily necessary because the topmost level on which is provided a public 70 hallway communicating with all the units, is provided on level 5.

In the modification of Figs. 6, 7 and 8, inclusive, the building 110 has four stories or levels, 101, 102, 103, 104, in vertical superposition.

75 The building is entered from the street

through door 112, opening into a stair well 114 extending to the roof 116. Levels 101 and 102 make up one duplex apartment and levels 103 and 104 make up the other duplex apartment in the building.

The living rooms of the lowermost apartment are on level 101 (see Fig. 7), comprising a living room 130, kitchen 133 and lavatory 135. The foyer 134, outside entrance door 122, opens onto stairwell 144. It will be noted that stairwell 114 opens only to but one level of each duplex apartment: onto level 101 of the lower apartment, and onto level 104 of the upper apartment. Access to level 102 within the lower apartment is provided by stairs 136 within the apartment between levels 101 and 102. On the bedroom floor 102 of the lower unit, I may provide a large bedroom 138, a smaller bedroom 140, and a toilet or bathroom 142. The room arrangement on level 103 is the same as on level 102, and Fig. 8 represents both levels 102 and 103, and the room arrangement on level 104 is the same as on level 101, Fig. 7 representing both levels 101 and 104.

It will thus be seen that in this arrangement also the successive apartment units in the tier have been reversed, so that the bedroom of one apartment unit is in immediate proximity to the bedroom of the adjacent unit. As will be obvious, my invention applied to a six- or eight- or ten- or more-storied building, would also bring the living rooms into immediate proximity, and in each interior unit, the bedroom would be adjacent the bedroom of the unit above (or below), and the living rooms would be adjacent the living rooms of the unit below (or above).

In the form of invention of Figs. 9 and 10, I have combined single-story or level units with duplex units, retaining in the duplex units the successive reversal arrangements of my other forms. Thus stories 201 and 202 make up one duplex unit, with the living rooms on story 202 and the bedrooms on story 201. The next two stories 203 and 204 also make up duplex units, but the arrangement is reversed, the living rooms being on the lower story 203 and the sleeping rooms on story 204. I then provide a number of stories 205 and 206 having apartment units containing both living and bedrooms on the same story or level. Further, in this combination form of building, I may provide additional duplex units on floors 207, 208, 209 and 210, in both sets of duplexes, the arrangement is such that the living rooms of one duplex unit are spaced from the bedrooms of the adjacent duplex unit by an intermediate story or level, thereby reducing and minimizing the effects of sounds emanating from the living rooms of the adjacent duplexes.

Having now described my invention, what I claim and desire to secure by Letters Patent is:

1. In a multi-storied building construction, a plurality of vertically superposed apartment units, each unit occupying at least two stories, the living rooms being contained on one story and the sleeping quarters being contained on another story making up the unit, the story containing the sleeping quarters of one unit being spaced away from the stories of the units above and below containing the living rooms by at least one intervening story.

2. In a multi-storied building construction, a plurality of vertically superposed apartment units, each unit occupying at least two stories, the living rooms being contained on one story and

the sleeping quarters being contained on another story making up the unit, the arrangement of the stories in each unit being reversed with respect to the adjacent units above and below.

5. In a multi-storied building construction, a plurality of vertically superposed apartment units, each unit occupying at least two stories, the living rooms being contained on one story and the sleeping quarters being contained on another story making up the unit, the arrangement of the stories in each unit being reversed in successive superposed units, bringing the bedrooms of one unit into proximity with the bedrooms of the immediately adjacent unit.

10 6. A multi-storied building construction, as in claim 3, in which the living room story of one unit is in proximity with the living room story of the immediately adjacent unit.

7. In a multi-storied building construction, a plurality of vertically superposed apartment units, certain of which units occupy at least two stories and are in proximity to other units which occupy at least two stories, the two-story units having the living rooms on one story and the bedrooms on the other story thereof, the arrangement of the stories in each two-story unit being reversed with respect to the arrangement of the stories in the adjacent two-story unit.

15 8. A multi-storied building construction as in claim 5, in which the living room story of one two-story unit is in proximity to the living room story of the adjacent two-story unit.

9. A multi-storied building construction as in claim 5, in which the bedroom story of one two-story unit is in proximity to the bedroom story of the adjacent two-story unit.

20 10. A multi-storied building construction as in claim 5, in which the bedroom story of one two-story unit is spaced away from the living room story of the adjacent two-story unit by at least one intervening story.

15 11. In a multi-storied building construction, a plurality of series of apartment units above one another, each series occupying at least two levels and having a public hallway on one level, said public hallway communicating with each unit in the series, the adjacent series of units also having a public hallway on one level thereof, the public hallway of any one series of units being separated from the other level of the adjacent series by at least one intervening level.

25 12. In a multi-storied building construction, a plurality of series of apartment units above one another, each series occupying at least two levels and having a public hallway on one of the levels, said public hallway communicating with each unit in the series, the adjacent series of units also having a public hallway on one level thereof, the public hallway of any one series of units being separated from the other level of the adjacent series by at least one intervening level, the level arrangements of succeeding units being reversed with respect to one another.

30 13. In a multi-storied building construction, a plurality of series of apartment units above one another, each series occupying at least two levels, the units on one of the levels thereof having a communication therebetween, and on another of the levels thereof being normally independent of each other, the level arrangements of succeeding series of units being reversed with respect to the series above and below.

CHARLES H. SACKS.
